UNITED STATES PATENT OFFICE.

RAY C. SHERMAN, OF MILES CITY, MONTANA.

FURNACE-DOOR.

1,159,282.

Specification of Letters Patent.

Patented Nov. 2, 1915.

Application filed January 4, 1915. Serial No. 421.

To all whom it may concern:

Be it known that I, RAY C. SHERMAN, a citizen of the United States, residing at Miles City, in the county of Custer and 5 State of Montana, have invented certain new and useful Improvements in Furnace-Doors, of which the following is a specification, reference being had to the accompanying drawings.

10 This invention relates to certain improvements in furnace doors and has relation more particularly to a device of this general character especially designed and adapted for use in connection with blast furnaces or 15 the like wherein an intense heat is generated; and the object of the invention is to provide a novel and improved door wherein the possibility of the same burning out is substantially entirely eliminated and whereby the life thereof is greatly prolonged.

15 The invention consists in the details of construction and in the combination and arrangement of the several parts of my improved furnace door whereby certain important advantages are attained and the device is rendered simpler, less expensive and otherwise more convenient and advantageous for use, all as will be hereinafter more fully set forth.

20 0 The novel features of the invention will be carefully defined in the appended claims.

In order that my invention may be the better understood, I will now proceed to describe the same with reference to the accompanying drawings, wherein—

Figure 1 is an elevational view illustrating a door constructed in accordance with an embodiment of my invention in applied position; and Fig. 2 is a view in top plan, detached, of my improved door as herein embodied, the overflow pipe carried thereby being shown in fragment.

As disclosed in the accompanying drawings, F denotes a fragment of a furnace with which my improved door coacts, said door being herein disclosed as mounted for movement in a vertical direction. As herein set forth, my improved door comprises a hollow body of predetermined dimensions having its top open and adapted to contain water. It will be perceived that by having the top of the body open, the door is effectually prevented against injury thereto owing to the expansion of the steam generated therein.

The door A may be constructed in any desired manner as will best meet the require-

ments of practice, although I find it of advantage to have the upper marginal portion thereof reinforced by the stay bolts 1 or the like although, if preferred, this may be dispensed with. The upper portions of the face walls of the door A are tied or connected by the yoke 2 with which is suitably engaged a flexible member 3 disposed around the guide pulley 4 and secured to the operating member 5 whereby the door may be raised or lowered as required. It is also to be observed that the door A is counter-balanced by the weight 6, for a purpose which is believed to be self-evident. Discharging within the door A in close proximity to one side thereof is the vertically disposed pipe 7 leading from a suitable source of supply, the discharge end of the pipe 7 terminating a predetermined distance below the upper or 75 open end of the door in order to prevent splashing and the vertical pipe is of such a length as to afford no obstruction to the upward movement of the door. In close proximity to the opposite side of the door A, the 80 interior thereof has in communication therewith through the front face thereof the overflow pipe 8, said overflow pipe 8 having its bore of greater diameter than the bore of the supply pipe 7. This variance in diameters is necessary as the water delivered through the pipe 7 is under pressure. The overflow pipe terminates in the depending vertical portion 9 telescopically engaged within the vertically disposed portion 10 of 90 the discharge pipe 11 and such portions 9 and 10 are of such a length as to assure proper coaction therewith irrespective of the vertical adjustments of the door. It is also to be observed that the vertical portion 10 95 is of materially greater diameter than the vertical portion 9 in order to keep the water confined at all times. At a point a predetermined distance below the lowermost point of the vertical portion 9, the discharge pipe 100 is reduced, as at 12, to the size of the overflow pipe proper, and such portion 12 is adapted to lead to any suitable point of discharge. In view of the foregoing, it will be readily apparent that the door A will at 105 all times be kept cool, irrespective of the degree of heat within the furnace, as there is substantially a continuous circulation of water through the door.

From the foregoing description, it is 110 thought to be obvious that a furnace door constructed in accordance with my inven-

tion is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

15 1. A door for a furnace comprising a hollow body, members reinforcing the upper marginal portion of the body and intersect-

ing the same, and means for creating a continuous flow of fluid through the body.

2. A door for a furnace comprising a hollow body, members reinforcing the upper marginal portion of the body and intersecting the same, means for creating a continuous flow of fluid through the body, a yoke connecting the upper portions of the face walls of the door, and means coacting with said yoke for imparting vertical movement thereto.

In testimony whereof I hereunto affix my signature in the presence of two witnesses.

RAY C. SHERMAN.
